UNITED STATES PATENT OFFICE.

DE'ETTE B. COMBS, OF PHILADELPHIA, PENNSYLVANIA.

CARD-HOLDING DEVICE.

Application filed November 10, 1923. Serial No. 673,938.

This invention relates, generally, to improvements in devices for holding price-cards, display-cards, place-cards, and for similar purposes.

5 The invention has for its principal object to provide a cheap, easily manufactured and yet very efficient device for supporting a card or similar article, so that the same is not only conveniently presented to view, but 10 is firmly gripped by the supporting means in strong frictional engagement therewith, so that accidental separation or displacement of the card or the like from properly adjusted position is prevented. The invention 15 has for a further object to provide a novel construction of supporting base, which, although it may be made of light weight material, is nevertheless so constructed as to readily resist any tendency of 20 the same to be accidentally knocked or blown over. Another object of the invention is to provide a novel supporting base which may be made of a great variety of kinds of sheet material, which is of neat and attractive 25 appearance; and which, in its finished form, provides a considerable area of surface which may be utilized to receive decorative embellishment, or which may be utilized for the imprint thereon of desired advertising 30 matter.

Other objects of this invention, not at this time more particularly enumerated, will be clearly understood from the following detailed description of the same.

35 With the various objects of this invention in view, the same consists, primarily, in the novel construction of card support or holder hereinafter set forth; and, the invention consists, furthermore, in the novel arrangements and combinations of the various devices and parts, as well as in the details of the construction of the same, all of which will be hereinafter more fully described, and then finally embodied in the claim 40 appended hereto.

The invention is clearly illustrated in the accompanying drawings, in which:—

Figure 1 is a face view or front elevation of the novel supporting or holding member, 50 together with a novel display-card operatively engaged therewith so as to be firmly gripped and supported thereby; Figure 2 is a side elevation of the same; Figure 3 is a horizontal section, taken on line 3—3 in said Figure 1; Figure 4 is a vertical central 55 longitudinal section of the same; and Fig-

ure 5 is a plan view of a blank out of which the novel supporting or holding member is made.

Similar characters of reference are employed in all of the hereinabove described views, to indicate corresponding parts.

Referring now to said drawing, the reference character 1 indicates a hollow base-member or support which, in form, is of 60 conical shape having a substantially broad bottom or base. The said base-member is preferably made of any suitable flexible sheet material, such as paper, celluloid, fibre, metal, etc.; although, broadly considered, the said hollow base-member or support may be made in integral form in other 65 ways, as by molding the same out of a suitable plastic material, or by stamping or spinning the same out of sheet metal, or by 70 turning the same, the essential feature of the invention being the provision of a hollow substantially conical-shaped member 75 having the novel card gripping elements to be subsequently described.

In making up the novel hollow base-member or support by cheap quantity production methods, I prefer to use a suitable flexible or bendable sheet material, which may be cut into blanks, such as shown in Figure 80 5, thus providing a substantially semi-circular flat blank member α , provided along its straight or diametric edge, so as to extend from the center y thereof in both directions, with over-lap tongues or projections z . The blank member α is provided, 85 in the line of its vertical axis, at a suitable location intermediate the center y and the circumferential edge thereof, with a bow-shaped slot or cut-out portion s , which is 90 preferably semi-elliptical in shape, having converging ends directed toward the circumferential edge of the blank-member.

The blank-member having been produced in the form above-described, the same is 100 thereupon shaped into hollow-conical form, with the over-lap tongues or projections z overlapping one upon the other and extending downwardly from the apex of the conical form to the base thereof, as shown in 105 Figures 1 to 4 of the drawings. The overlapping tongues or projections z may be secured together in any suitable manner. I have, however, found it to be very convenient and satisfactory to secure said tongues 110 or projections together by means of one or more wire stitches or staples 2, as shown,

although I do not desire to limit myself necessarily to such means of fastening.

The result of the above-described operations produce the hollow-conical base member or support 1, having a substantially wide base and upwardly and inwardly sloping sides terminating at the upwardly directed apex. A device of this character, even though it be made of comparatively light weight sheet material, is adapted to produce a very firm and stable supporting member, capable of supporting comparatively heavy weight without crushing or becoming top-heavy and easily overbalanced; and also capable of supporting a generously sized card with little likelihood of the same being toppled over by ordinary moving air currents. When the blank *x* is shaped into conical form, the slot *s* defines an upwardly directed gripping tongue 3 which is concavo-convex in cross section, and which is opposed to and cooperates with a gripping edge 4 provided by the uppermost boundary of the slot *s*, and which owing to the spaced relation 25 of the edges of the slot *s* tends to fall within the opening defined by the gripping edge 4 of the latter. The card 5 or other piece to be supported by the base or support 1 is disposed with its lower end inserted between 30 the gripping tongue 3 and the gripping edge 4, and is thrust down between such parts until stopped by the converging ends of the slot. Owing to the conical shape or contour of the base or support 1 which gives convexity in cross-section to the gripping tongue 3, in combination with the semi-elliptical shape of the slot *s*, whereby the tongue tends to fall within the opening thereof, the lower end of the inserted card 35 40 45 is flexed at the corners 5', thereby placing the card itself under a tension which aids or is auxiliary to the gripping effect of the gripping-tongue 3, so that the card is firmly held against accidental displacement or separation from the base or support 1.

The novel form of base or support 1 lends itself admirably for the stable support of display cards, in upright and slightly rearwardly inclined position, so that small articles secured to the face of the display card are neatly and attractively displayed, all of which will be understood from an inspection of Figures 1, 2 and 4 of the drawings. 50 55 The novel hollow conical base or support 1 may be made in various sizes as desired,

and is adapted, by virtue of the novel gripping elements, to securely support sign or advertising cards, display cards, place cards, price cards and all kinds of similar devices. 60 The inclined sides of the conical base or support 1 also provide in themselves a considerable area of space which may be employed for the reception of advertising matter when used for trade purposes, or for 65 decorative embellishment when used for social purposes, such, for example, as place card supports and the like for festival occasions such as Christmas, Independence Day, 70 Halloween, etc.

The hollow conical form of the novel card holding device renders the same of considerable strength and durability, so that, although it may be cheaply made of comparatively light weight sheet material, it is none-the-less strong and efficient for the purposes in view.

My novel hollow conical form of card holding device possesses, in addition to the advantages already above pointed out, the further advantage of convenient shape for packing together in quantities for distribution, since the devices may be compactly nested together in desired numbers to produce a shipping package of comparatively 85 small bulk, and in which the nested arrangement of the devices one with another in itself produces a mutual reinforcement thereof tending to protect the same against damage or injury during transit, etc. 90

I claim:

A card holder, comprising a substantially semi-circular blank of sheet material, said blank being rolled to form a hollow conical member with the meeting portions of its 95 diametric edge overlapped and secured together to retain said blank in the aforesaid conical form, and said conical member having a transverse semi-elliptical upwardly bowed slot having vertically spaced apart 100 edges which converge toward the respective ends thereof, the lower edge of said slot defining an upwardly directed gripping tongue adapted to engage a card inserted in said slot and laterally flex the same so as to frictionally bind it against the upper edge of said slot.

In testimony that I claim the invention set forth above I have hereunto set my hand this 5th day of November, 1923.

DE'ETTE B. COMBS.
